UNITED STATES PATENT OFFICE.

CHARLES A. GREELY, OF OAKLAND, CALIFORNIA.

ILLUMINATING DOOR-KNOB.

1,128,307.

Specification of Letters Patent. Patented Feb. 16, 1915.

... on filed June 22, 1914. Serial No. 846,659.

To all whom it may concern:

Be it known that I, CHARLES A. GREELY, a citizen of the United States, residing at Oakland, in the county of Alameda, State 5 of California, have invented certain new and useful Improvements in Illuminating Door-Knobs; and I do hereby declare the following to be a full, clear, and exact description of the invention, such as will enable others 10 skilled in the art to which it appertains to make and use the same.

This invention relates to door knobs and has for its object the provision of a door knob carrying means whereby light may be 15 thrown upon the escutcheon plate so that the key holes may be readily found in the dark.

An important object is the provision of a door knob having an electric lamp disposed and protected therein and adapted to 20 throw light upon the escutcheon plate.

A further object is the provision of a door knob of this character provided with means readily engageable by the operator's fingers for closing the circuit to energize the lamp.

Still another object is the provision of a door knob of this character so constructed that it may be readily taken apart to afford 25 easy access to its interior in case of any necessity for repairing the mechanism contained therein.

Still another object is the provision of a door knob of this character which will be simple and inexpensive in manufacture, efficient and positive in operation and a general improvement of the art.

With these and other objects and advantages in view, the invention consists in the novel construction, arrangement and combination of parts as will be hereinafter 40 more fully described and illustrated in the accompanying drawings in which—

Figure 1 is an edge view of a door having my improved door knob applied thereto, Fig. 2 is a vertical longitudinal sectional view through the knob and door, Fig. 3 is a sectional view on the line 3—3 of Fig. 2, and Fig. 4 is a face view of the knob.

Referring more particularly to the drawings, the numeral 5 designates a door provided with the usual latch, lock bolt 6, plate 7, escutcheon plate 8 provided with the usual key holes, and the latch operating bar 11 projecting through the escutcheon plate 8. The parts just described are old and well 55 known in the art and form no part of the present invention.

My improved door knob is primarily for the purpose of rotating the latch actuating bar 11 and comprises a shell formed in two sections 12 and 13, the section 12 being provided with a laterally extending sleeve 14 secured upon the bar 11 by any suitable means, as for instance a screw 15. The section 13 conforms in contour to the section 12 and is removably secured thereto as by 60 means of screws 16 which pass through the section 13 and engage lugs 17 formed on or secured to the section 12 adjacent its open end.

Below the sleeve 14 the section 12 is provided with an opening 18 adjacent which is secured on the interior of the section 12, a bracket 19 which comprises an angular arm 20 secured to and insulated from the section 12 as by a bushed screw 21, and carrying at its free end a threaded socket shell 22 which is open at both ends and which is adapted to receive an electric lamp 23, the bulb of which extends within the opening 18. The bracket 19 and socket shell 22 are formed 75 70 75 80 of metal. A leaf spring 24 is secured upon and insulated from the inner side of the section 12 at a point above the sleeve 14 as by a bushed screw 25, and is bent to extend adjacent the section 13 and is then rebent 85 to form a portion 26 adapted to be contacted with the contact button 27 on the end of the lamp 23.

At a point below the plate 7 the door 5 is provided with a recess 28 in which is 90 disposed preferably a dry battery 29 which has its terminals connected with the screw 25 and the screw 21 by wires 30 and 31 respectively. A plate 32 is hingedly secured upon the lower end of the plate 7 95 for closing the recess 28.

In order to close the circuit to energize the lamp 23 so that light will be projected thereby upon the escutcheon plate 8 I provide a push button 33 which extends through 100 an opening formed centrally through the section 13 and which abuts against the leaf spring 24. The resilience of the spring 24 normally presses the push button 33 outwardly with its enlarged portion 34 bearing against the section 13.

When it is desired to throw light upon the key holes it is merely necessary that the operator press inwardly upon the push button 33 whereupon the end 26 of the 110 spring will contact with the button 27 on the lamp 23 whereupon current will flow

from the battery 29 through the wire 30, screw 25, spring 24, contact button 27, through the filament of the lamp, through the socket shell 22, bracket 19, screw 21, and 5 wire 31 back to the battery, thereby causing the lamp to incandesce until pressure is removed from the push button 33.

From the foregoing description and a study of the drawings it will be apparent 10 that it is a very simple matter to illuminate the escutcheon plate to facilitate the insertion of the key within the key holes without the necessity for any exasperating fumbling in the dark.

15 It will be understood that the provision of the lamp and its associated parts within the door knob does not in any way interfere with the retraction of the latch bolt. Furthermore my device presents a neat and 20 attractive appearance as the wires pass through the plate 8 and through suitable grooves to the battery.

It will be readily understood that I reserve the right to make such changes as 25 will not depart from the spirit of the invention and will therefore be included within the scope of the subjoined claim.

Having thus described my invention, I claim:

In combination with a door lock having a 30 key hole therein, a hollow door knob provided with an aperture, an electric lamp disposed adjacent said aperture, an electric battery disposed in the door, a bracket secured within said door knob, a socket on said bracket 35 receiving said lamp, said bracket being connected with one terminal of said battery, a leaf spring secured within said door knob and connected with the other terminal of said battery, said leaf spring extending adjacent the front wall of said knob and being bent to form a contact member and a push button extending centrally through the front wall of said knob and engaging said spring whereby the contact portion of 40 said spring may contact with the end of said lamp.

In testimony whereof, I affix my signature, in the presence of two witnesses.

CHARLES A. GREELEY.
